UNITED STATES PATENT OFFICE.

WILLIAM K. SCHAEFER, OF FAIRMONT, WEST VIRGINIA.

OVEN.

1,148,863.

Specification of Letters Patent.

Patented Aug. 3, 1915.

Application filed July 17, 1914. Serial No. 851,592.

To all whom it may concern:

Be it known that I, WILLIAM K. SCHAEFER, a citizen of the United States, residing at Fairmont, in the county of Marion and 5 State of West Virginia, have invented certain new and useful Improvements in Ovens, of which the following is a specification.

This invention relates to stoves and more 10 particularly to revoluble ovens therefor, having primarily for its object to permit of an equal distribution of radiant heat to all parts of the oven to expedite cooking of articles carried in the oven.

15 Another object is to provide an oven which may be associated with standard types of stoves without materially increasing their cost, and may be readily operated by any one without danger of being burnt, 20 since the oven is operated by means remote therefrom.

A further object is to utilize a plurality of article carriers which are detachable, and which are simultaneously operated by the 25 means mentioned above.

A still further object resides in the provision of a simple and efficient means which not only aids in the support of the article holders, but likewise, prevents their accidental displacement when the oven is 30 revolved.

Other objects as well as the nature, characteristic features and scope of my invention will be more readily understood from 35 the following description taken in connection with the accompanying drawings and pointed out in the claims forming a part of this specification.

Referring to the drawings: Figure 1 is a 40 side elevational view of a stove having an oven constructed in accordance with my invention, showing the oven door removed therefrom, Fig. 2 is a top plan view of the oven, Fig. 3 is a bottom plan view of my 45 improved device showing the spur-gear in operative connection with the teeth on the base of the oven frame, whereby the latter is rotated when the spur-gear is operated. Fig. 4 is a detailed enlarged fragmentary 50 sectional view of the oven frame illustrating the manner in which the article holders are held from displacement when the oven is rotated, at the same time, permitting of the removal of the article holders, Fig. 5 is a 55 detailed enlarged fragmentary view of the stove showing the gearing mechanism by

which the oven frame is rotated, and Fig. 6 is a side elevational view of one of the uprights of the frame illustrating the manner in which it is engaged with the top and bottom of the frame. 60

In the drawings wherein is illustrated the preferred embodiment of this invention, in order to illustrate the application thereof, a stove 5 is provided which may be of the usual or any desired configuration, in the present instance provided with the usual openings 6 in which my improved oven, generally designated 7, is mounted. 65

The oven in the present instance comprises a frame which has a base 8 which is shown as consisting of an annular ring provided with teeth 9 on its inner periphery and having rollers 10 mounted in equidistant relation in the base, thereby permitting 70 the ring to be revolved on the lower face of the oven opening 6, the teeth 9 being engaged in mesh with complementary teeth of a spur-gear 11, the latter being in connection with a beveled gear 12, said beveled gear 80 arranged beneath the base of the oven opening 6 and being in mesh with a corresponding beveled gear 13, the gear 13 being in connection with a crank 14 by which it is operated. As shown to advantage in Fig. 85

1, the crank 14 is carried exterior of the stove and beneath the oven opening 6 thereof, so as to eliminate the necessity of persons placing their hands in connection with the oven frame when it is desired to rotate 90 the same. A spider-web disk 15 is fixedly carried by the ring 8 and forms a supporting base which has extending upwardly therefrom a plurality of uprights 16, the upper terminals of the latter being in engagement with the upper end of the frame 95 17, the latter comprising a body 17' having arms 17² radiating therefrom, the outer terminals of the arms being in engagement with the lower face of an annular ring 17³, 100 each of said arms being secured to the upper end of one of the uprights 16, as shown to advantage in Fig. 6.

Each of the uprights 16 is provided with a plurality of notches 18, which are adapted 105 for the reception of spider disks 19, the latter comprising supports or holders upon which articles to be cooked are placed. Each of the disks 19 is preferably made of metal and is detachably associated with the uprights 16, so as to be readily removed when 110 so desired.

In order to prevent the accidental displacement of the disks 19, a locking bar 20 is provided which is pivotally engaged, as indicated at 21, with a foot 22, the latter being mounted on the supporting disk 15 and having a finger 23 extending from the upper terminal thereof which engages through a complementary opening in the lower of the spider-web disks 19. The bar 20 is provided with notches 24 on its inner margin which correspond to the notches 18 of the uprights 16, thereby assisting in the supporting of the spider-web disks 19, and at the same time, permitting their ready removal when it is so desired.

Slidably mounted on the upper end of the bar 20 is a keeper 25, in the present instance comprising a rod, one end 26 of which is turned at right angles to the body to provide a handle, and the opposite end bent to provide a substantially U-shaped structure 27, which engages over the top 17 of the frame of the oven, said keeper being held from displacement by guides 28, as shown to advantage in Fig. 1. By the provision of the keeper 25, it is seen that the rod 20 is locked in engagement with the upper end 17 of the frame of the oven, at times, in order to prevent accidental displacement of the disks 19 when the oven is rotated. To prevent accidental displacement of articles which are placed on the disks 19, semicircular rods 29 are associated with certain of the uprights 16, between the disks 19, said rods also bracing the members 16 from displacement.

In operation, assuming that the bar 20 has been swung out of engagement with the disks 19 and articles have been placed on the latter, the bar 20 is then returned to its upright position and having the notches 24 thereof engaged with the disks 19, as shown to advantage in Fig. 4, the U-shaped end 27 of the keeper 25 being engaged over the top 17 of the frame 17, permitting the oven to be rotated without danger of the disks 19 being displaced. In order to rotate the oven frame, pressure is exerted on the crank 14 which imparts motion to the spur-gear 11, transmitting motion to the ring 8, the latter in turn causing the rotation of the frame 17, in view of the fact that the supporting disk 15 is fixedly secured to the ring 8. The disk 15 is pivotally mounted on an axis 30, the latter being mounted on the bottom of the oven opening 6, thereby causing the oven to operate in a predetermined plane at all times, at the same time, preventing its bodily displacement. In removing articles from the disks 19, and 15, the keeper 25 is first disengaged after which the bar 20 is swung outwardly beyond the stove and the article is removed from the disks 19. Should it be

desired to remove an article or articles from the disk 15, and the articles are of such a size as to prevent their being readily removed between the foot 22 and the adjacent upright 16, the lower of the disks 19 is disengaged from the finger 23, thereby disengaging the foot 22.

It will be understood that the above description and accompanying drawings comprehend only the general and preferred embodiment of my invention and that various minor changes in details of construction, proportion and arrangement of parts may be made within the scope of the appended claims and without sacrificing any of the advantages of my invention.

Having thus fully described my invention, what I claim as new and desire to secure by Letters Patent is:

1. In combination with a stove, a revolvable oven therefor including a frame, said frame comprising a base having a plurality of uprights extending therefrom, the upper terminals of the latter being engaged with a circular member, spider-web disks detachably carried by said uprights, and means for locking said disks in engagement with said uprights to prevent the accidental displacement of said disks, and permitting of their expeditious removal at the option of the operator.

2. In combination with a stove, an oven therefor including a frame revolvably associated with the stove, said frame comprising a base having uprights extending therefrom, the latter being in connection with a circular member at their upper terminals, means in connection with said base and being operable remote from said oven to operate said frame, disks carried by said uprights, and a locking bar in connection with the base of said frame adapted to aid in the support of said disks and prevent their accidental displacement during the rotation of the frame.

3. In combination with a stove, an oven therefor including a frame revolvably mounted on the stove, means in connection with said frame for rotating the same, article carrier disks detachably mounted in the frame, and a locking bar mounted on the base of said frame for engagement, at times, with said disks to prevent their accidental displacement, and adapted to be disengaged from the disks and to be swung therebeyond when the articles carried by the disks, or the disks themselves are to be removed.

In testimony whereof I affix my signature in presence of two witnesses.

WILLIAM K. SCHAEFER.
